POWER CLAMP

Leland F. Blaft, Grosse Pointe Woods, Mich.
(24121 Mound Road, Warren, Mich.)
Filed Mar. 11, 1964, Ser. No. 351,005
4 Claims. (Cl. 269—32)

This application relates to cylinder operated power clamps.

In my prior Patent No. 3,116,058, of December 31, 1963, I disclose a cylinder operated power clamp wherein a carrier reciprocates in a tube under the influence of power means such as a power cylinder and piston for effecting movement of a clamp. As described in said patent, the carrier fits tightly within the tube to provide an air cushion between the carrier and the closed end of the tube with the clamp being connected to the open side of the carrier at the open side of the tube.

It is an object of the present invention to improve the construction disclosed in the foregoing patent by enlarging the cross-sectional area of the carrier, and by reducing the friction between the carrier and the tube while at the same time preserving to a maximum extent the air tight fit between the carrier and the tube. This is accomplished in the present construction by forming the carrier of rectangular cross-section complementary to the rectangular cross-section of the interior of the tube and then providing frictionless rollers properly mounted between the carrier and the tube so that while the air tight fit between the carrier and the tube is maintained to a maximum extent, nevertheless the carrier will reciprocate freely within the tube on the rollers and thus friction is reduced.

Several different embodiments of the foregoing have been disclosed in the appended drawings which are confined to the details of construction of the carrier and the tube per se, reference being had to the disclosure of the aforesaid patent whose disclosure is hereinto incorporated by reference for a complete understanding of the clamps.

In these drawings:

FIG. 1 is an elevation view of the clamp.

FIG. 2 is a right end view.

FIG. 3 is an elevation view of one form of carrier, per se.

FIG. 4 is a right end view of FIG. 3.

FIG. 5 discloses a modified form of carrier, per se, in side elevation view.

FIG. 6 is a right end view of FIG. 5 but showing tube parts as well.

FIG. 7 discloses another modified form of a carrier, per se, in side elevation.

FIG. 8 is a right end view of the carrier of FIG. 7 with associated tube parts also being shown.

As stated above, the invention hereof will best be understood upon reference to the disclosure of the aforesaid Patent No. 3,116,058 whose disclosure is incorporated hereinto by reference.

The attached drawing discloses a support 11 which mounts the clamp hereof, the latter including a clamping arm 16 which may be moved by the means hereof for the purposes of clamping workpieces W-W' in relation to an anvil A and support 11.

The invention hereof relates to a power actuated means, mounted upon the support 11, for moving the clamp arm 16.

The mounting for the means includes a base 17 on said support formed with a rectangular cross-section tube 22, the latter being unitary with a power cylinder 25 having a piston which may be air operated to reciprocate a rectangular cross-section carrier 35 within the tube 22. The connection between the piston of the power cylinder 25 and the carrier 35 within the tube 22 is established

2

through a tube rod 32 extending through a closed end 23 of the tube 22.

It will readily be understood that to those skilled in the art and as described in said patent that when the tube rod 32 is reciprocated under the influence of the piston in power cylinder 25, carrier 35 is likewise reciprocated.

Tube 22 has not only the closed end 23 but also an open end exposing the right end of the carrier 35 and enabling it to be connected by link 24 through the open end of the tube to the clamp arm 16, utilizing pivots 26 and 27.

It is important to preserve the air tight fit between the rectangular carrier 35 and the rectangular tube 22 to the maximum extent possible and this can be accomplished simply by making carrier 35 in a form and dimension tightly fitting within tube 22. This, however, sets up the problem of increased friction between carrier 35 and tube 22. To effect a balance and compromise between the desire for maximum air tight fit between the carrier and the tube and at the same time for minimum friction between the carrier and tube, the arrangements of this application have been developed and will now be described.

In each of the three modifications here shown, the carrier is of rectangular cross-section conforming to the rectangular cross-section of the tube providing maximum pressure area and maximum air tight fit between the carrier and the tube.

In the form of FIGS. 1 to 4, the carrier 35 has its sides recessed to contain friction reducing rollers 60 mounted on an axle 61 in a cross-bore of the carrier 35. These rollers 60 support and guide the carrier in its reciprocal movement in tube 22 and reduce friction between the carrier and the tube.

In FIGS. 5 and 6, the carrier 35 is provided with two roller chains 66 and 67 on opposite sides of the carrier and embracing all four edges of the carrier for friction reducing.

In FIGS. 7 and 8, the four inner edges of the tube 22 are formed with hardened inserts or tracks 72 and two sets of roller bearings 73 are provided between the four edges of the carrier 35 and the four tracks 72 for friction reducing.

It will be observed that by forming the carrier and the tube of complementary rectangular cross-section and by providing friction producing rollers in the manner herein disclosed, maximum pressure area, maximum air tight fit, and minimum friction between the carrier and the tube are established.

Now having described the construction herein disclosed, reference should be had to the claims which follow.

I claim:

1. A unitary clamping means including a horizontally arranged rectangular cross-sectional tube having a closed end and an open end;

a tube rod in said tube passing through its closed end; pneumatic means unitary with said tube and having a

piston rod connected to said tube rod for moving the

tube rod along its axis and the axis of the tube;

a carrier secured to said tube rod adjacent the open end of the tube and disposed in the tube for reciprocating movement therein;

a clamp;

means pivotally connecting the carrier to the clamp; said carrier being of rectangular cross-section and substantially completely filling said tube to provide an air cushion in said tube to the side of said carrier between the carrier and the closed side of the tube; and

friction reducing guide rollers on and carried by said

carrier enabling frictionless reciprocation of said carrier in said tube.

2. Clamping means according to claim 1, wherein the rollers are large diameter rollers on opposite sides of the carrier and connected by an axle in a cross-bore of the carrier. 5

3. Clamping means according to claim 1, wherein the rollers are parts of two roller chains at opposite sides of and surrounding the carrier at its four edges and extending lengthwise of the carrier.

4. Clamping means according to claim 1, wherein the rollers are two sets of free roller bearings at opposite sides of the carrier and at its four edges, and bearing

tracks in the tube for the roller bearings at the four edges of the carrier.
